UNITED STATES PATENT OFFICE.

ACHILLO FABRIZIO, OF ELKTON, MARYLAND.

TORPEDO.

Application filed November 25, 1924. Serial No. 752,114.

To all whom it may concern:

Be it known that I, ACHILLO FABRIZIO, a subject of the King of Italy, residing at Elkton, in the county of Cecil and State of Maryland, have invented certain new and useful Improvements in Torpedoes, of which the following is a specification.

My invention relates to torpedoes and more particularly to the casing enclosing the explosive material.

The objects are to provide a casing for enclosing explosive material which will be of practically uniform strength; which will be of simple and strong construction, and which may be quickly made at low cost.

These objects, and other advantageous ends which will be described hereinafter, I attain in the following manner, reference being had to the accompanying drawings in which—

Figure 1 is a central section through a torpedo constructed in accordance with my invention,

Figure 2 a fragmentary perspective view illustrating a step in the making of the torpedo casing, and

Figure 3 an enlarged central section through one of the casing sections shown in Figure 1.

Referring to the drawings, 1 indicates the casing of a torpedo and 2 the explosive material therein. The casing consists of an inner cup 3 and an outer cup 4 of substantially equal length. Each of the cups is open at one end and closed at the other end by peening the edge 5 of the cylindrical wall to form a flange on which a disk 6 rests and to which it is glued or otherwise secured.

The bent edge or flange 5 may be produced in various ways, such as by softening the end of a paper tube and pressing the edges inward or by winding a strip of paper around the end of a mandrel and folding one edge of the strip over the end of the mandrel.

I prefer to use the latter method of forming the flange as follows: A strip of paper 7, coated on one side with adhesive material, is wound around the end of a mandrel 8 in such manner that its edge 9 overhangs

the end of the mandrel. This edge, as the strip is wound, is folded over the end of the mandrel as shown at 10 in Figure 2. The folded edge, becoming cramped as it nears the center of the mandrel, forms small tucks 11. The strip is wound around the mandrel a sufficient number of times to make up a casing of the proper strength, after which the wound strip is removed from the mandrel. The folded edge 10 of the strip with

the small tucks 11 therein forms the flange 5. Disk 6 is then forced into the cup and glued to the flange. The disk and flange are compressed so that the small tucks 11 are practically unnoticeable, and the flange 5 becomes practically an integral part of the cup. The adhesive material on the strip, being moistened, causes the wound wrappings of the cup to stick to each other and form a strong sidewall. The inner cup 3 is made

on a mandrel of smaller diameter than the outer cup 4 which fits over it. Each of the cups is made of practically the same length so that when the explosive material is placed on the inner cup and the outer cup slipped over it and glued or otherwise secured there-

to, as shown in Figure 1, the cylindrical wall of the torpedo will be of a strength twice as great as either of its ends.

The casing above set forth may be used with fireworks when a light and strong casing is required for enclosing an explosive.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A device of the character described including a pair of telescoping cups enclosing explosive material and having an inwardly extending flange, and a disk secured to the inner side of the flange to form a bottom of the cup.

2. A device of the character described including a pair of telescoping cups enclosing explosive material and having their side walls made of a series of layers of strip material with one edge of the strip bent inwardly to provide a flange, and a disk secured to the inner side of the flange.
- 5

In testimony whereof I have signed my name to this specification in the presence of two subscribing witnesses.

ACHILLO FABRIZIO.
